F. G. Fischer,

Attorney.

UNITED STATES PATENT OFFICE

2,312,252

SPRINKLER HEAD

John M. Johnson, Kansas City, Mo.

Application November 16, 1940, Serial No. 365,982

5 Claims. (Cl. 169—38)

My invention relates to improvements in sprinkler heads for employment in automatic sprinkler systems such as are installed in buildings for protection against fires.

Sprinkler heads sometimes get out of order and open accidentally when there is no fire to extinguish. When this occurs considerable property loss is entailed by water discharged from the sprinkler system and a false alarm is transmitted that will call out the fire apparatus.

An object of my invention is to prevent accidental opening of the sprinkler heads which may be associated with local electric alarm circuits through which trouble in any of the sprinkler heads of the sprinkler system may be located and repairs made without sending in a false alarm or interrupting the sprinkler service.

A further object is to provide a sprinkler head which may be associated with an electric fire alarm circuit so that in the event a fire occurs and causes the sprinkler head to open an alarm will be transmitted to call out the fire apparatus.

In order that the invention may be fully understood, reference will now be had to the accompanying drawing, in which—

Fig. 1 is a front elevation of the sprinkler head.

Fig. 2 is a combined side elevation and vertical section of the sprinkler head in closed position.

Fig. 3 is an irregular cross section on line 3—3 of Fig. 2.

Fig. 4 is a broken vertical section showing the sprinkler head in open position.

Fig. 5 is a diagram of the circuits.

Referring in detail to the different parts, 2 designates the sprinkler head which consists of a tubular shell provided at its upper end with a valve seat 6 and at its lower end with screw threads 8 so that it may be readily connected to a pipe of the sprinkler system, not shown. A composite valve comprising elements 10, 14 and 16 is adapted to rest upon the seat 6 to close the upper end of the passageway 12 extending vertically through the sprinkler head. The element 16 consists preferably of insulation and has an upwardly extending axial boss 18 for a purpose which will hereinafter appear.

The valve is normally held seated by a plurality of parts consisting in the present instance of a pair of members 20 and 21, a similar pair 22 and 23, and two adjustable elements 24 and 25. The members 20 and 22 bear upon and hold the valve to its seat and their lower ends are spaced apart by the boss 18, diametrically opposed portions of which they engage.

The members 20 and 22 have shoes 26 and 27 55

extending outwardly at right angles from their respective upper ends for the reception of feet 29 and 30 extending outwardly at right angles from the lower ends of the respective members 21 and 23. The feet 29 and 30 are normally held in the shoes with solder 32 and 34 adapted to fuse at a predetermined temperature. The feet 29 and 30 are provided near their outer distal ends with upwardly extending tubular portions 35 and 36 in which the upper ends of coil springs 38 and 40 are seated. The lower ends of the springs press against the upper side of the respective shoes 26 and 27 to dislodge the feet therefrom on fusing of the solder. The tension of the springs 38 and 40 is regulated by the adjustable elements 24 and 25, and by screws 42 and 44 threaded in the upper ends of the respective tubular portions 35 and 36. The feet 29 and 30 are provided at their inner or adjacent ends with upwardly extending bosses 46 and 48 which are internally threaded for reception of the lower threaded portions of the elements 24 and 25, the upper ends of which are tapered and seated in insulators 50 and 52 secured in the underside of respective abutments 54 and 56 depending from diametrically opposed portions of a disk 58 integral with the upper part of a yoke 60 extending upwardly from diametrically opposed portions of the sprinkler head. The disk 58 has a water spreader 59 fixed thereon for spreading the water from the sprinkler system as it is discharged through the sprinkler head. The elements 24 and 25 have rectangular intermediate portions 62 and 64, respectively, whereby they may be rotated with a wrench or other suitable tool to force the two sets of members 20, 21 and 22, 23 downward to compress the springs 38 and 40 and to hold the valve to its seat against the pressure in the sprinkler system. The pressure on either set of members is sufficient to hold the valve to its seat should one of the sets become dislodged, but in the event both sets become dislodged the pressure of the water will unseat the valve.

When either set of members 20, 21, or 22, 23 become dislodged from any cause as by breakage of a defective member, or disintegration of the fusible solder, notice of the trouble may be given by local electric signal circuits, including wires 67 and 68, to indicate the location of the particular sprinkler head at which the trouble occurs. A fire alarm circuit is also provided for sending an alarm to the fire department in the event a fire occurs and melts the fusible alloy of both sets of members 20, 21 and 22, 23.

Fig. 5 shows normally closed local circuits 67,

68, 69 and 70 for two sprinkler heads, but this number may be varied according to the number of sprinkler heads employed in the sprinkler system. Each local circuit includes a source of electrical energy 72, an electromagnet 74, a circuit wire 76, and either a set of members 20 and 21, or 22 and 23.

Should the set of members 20 and 21 of circuit 67 become disconnected from any cause and thus open the circuit, the associated electromagnet 74 will become deenergized and permit its armature 78 to close a signal circuit comprising the armature 78, a branch wire 80, a visual signal 82, a line wire 83, a source of electrical energy 84, an audible signal 86, and a wire 87. The audible signal 86 attracts attention and the visual signal 82 indicates the particular location of the trouble.

If the set of members 22 and 23 of circuit 68 becomes dislodged instead of the members 20 and 21, the associated electromagnet becomes deenergized and permits its armature to close a circuit comprising the armature, a branch wire 88, a visual signal 90, the line wire 83, the alarm signal 86, a line wire 92, and a branch wire 94. The armatures 78, associated with the electromagnets 74 of the local circuits 69 and 70, are connected by branch wires 96 and 98 to the respective line wires 83 and 92 and adapted to contact the terminals of branch wires 100 and 102 connected to the respective line wires 92 and 83 and equipped with visual signals 104 and 106, respectively, so that if either of the local circuits 69 and 70 are opened the audible signal 86 and the visual signal 104 or 106 will become energized.

In the event that a fire occurs and melts the fusible alloy in all of the local circuits a fire alarm will be transmitted to fire headquarters through branch wires 108, 110 and 112, contacts 114 carried by but insulated from the respective armatures 78, and line wires 116 and 118, respectively. The line wires 116 and 118 receive current from a source 120 and are equipped with an audible signal 122.

The flow of current through the different circuits when closed is indicated by the dotted arrow heads.

While I have shown and described a preferred embodiment of my invention, I reserve all rights to such changes and modifications as properly fall within the spirit and scope of the invention as claimed.

Having thus described my invention, what I claim and desire to secure by Letters Patent is:

1. A sprinkler head comprising a tubular shell having an inlet end for connection with a sprinkler system and a discharge end having a valve-seat, a valve resting upon said seat, a plurality of separable members assembled in pairs which are mounted upon the valve and either pair of which is adapted to normally hold the valve seated, each pair of members having a foot on one member and a shoe on the companion member to receive said foot, means for pressing each pair of members downward to hold the valve seated, and fusible means for normally securing each foot in its shoe to hold the respective pairs of members in assembly.

2. A sprinkler head comprising a tubular shell having an inlet end for connection with a sprinkler system and a discharge end having a valve-seat, a valve resting upon said seat, a plurality of separable members assembled in pairs which are

mounted upon the valve and either pair of which is adapted to normally hold the valve seated, each pair of members having a foot on one member and a shoe on the companion member to receive said foot, means for pressing each pair of members downward to hold the valve seated, fusible means for normally securing each foot in its respective shoe, and spring means for dislodging the foot from the shoe on fusing of the fusible means.

3. A sprinkler head comprising a tubular shell having an inlet end for connection to a sprinkler system and a discharge end having a valve seat, a valve resting upon said seat and provided with an upwardly extending boss, a plurality of upper and lower members assembled in pairs, the lower ends of the lower members bearing upon the valve and engaging diametrically opposed portions of the boss, the upper members of each pair being superimposed on the lower members and each having an upwardly extending internally threaded boss, fusible means for normally securing the upper members in assembly with the respective lower members, upwardly extending adjustable members threaded at their lower end in the respective last-mentioned bosses and adapted to exert pressure thereon to hold the valve seated, and a yoke extending upwardly from the tubular shell and provided at its upper portion with means in which the upper ends of said adjustable members are seated.

4. A sprinkler head comprising a tubular shell having an inlet end for connection to a sprinkler system and a discharge end having a valve seat, a valve resting upon said seat, a plurality of upper and lower members assembled in pairs, the lower ends of the lower members bearing upon the valve, the upper members of each pair being superimposed on the lower members and each having an upwardly extending internally threaded boss, fusible means for normally securing the upper members in assembly with the respective lower members, upwardly extending adjustable members threaded at their lower end in the respective last-mentioned bosses and adapted to exert pressure thereon to hold the valve seated, a yoke extending upwardly from the tubular shell and provided with a disk, and abutments depending from said disk and provided with seats for the upper ends of the respective adjustable members.

5. A sprinkler head comprising a tubular shell having an inlet end for connection with a sprinkler system and a discharge end having a valve-seat, a valve resting upon said seat, a plurality of separable members assembled in pairs which are mounted upon the valve and either pair of which is adapted to normally hold the valve seated, each pair of members having a foot on one member and a shoe on the companion member to receive said foot, means for pressing each pair of members downward to hold the valve seated, fusible means for normally securing each foot in its shoe to hold the respective pairs of members in assembly, upwardly extending adjustable members threaded at their lower end in the respective last-mentioned bosses and adapted to exert pressure thereon to hold the valve seated, a yoke extending upwardly from the tubular shell, a disk at the upper end of said yoke provided with seats for the upper ends of the respective adjustable members, and a water spreader superimposed upon said disk.

JOHN M. JOHNSON.
